SAFETY HASP KEEPER

Thomas H. Mason, Peoria, Ill.

Application August 9, 1947, Serial No. 767,809

7 Claims. (Cl. 292—287)

1

This invention relates to a safety hasp keeper for use on emergency exit doors and more particularly for use on doors on government bonded premises such as registered distilleries, internal revenue bonded warehouses, and the like, which are normally kept secured on the inside by government locks.

The object of the invention is to provide a safety hasp keeper having a keeper element which is made of a material, such as hard lead, which may be severed fairly easily, and with which there is associated a knife member which may be struck to shear off said element, thus permitting emergency opening of the door without removing the lock which normally locks the hasp to the keeper.

Other objects and advantages of the invention will appear from the following detailed description taken in connection with the accompanying drawings, wherein I have shown a preferred embodiment of the invention.

Referring to the drawings:

Fig. 1 is an elevational view of the inside of a door and frame with the safety hasp keeper applied thereto;

Fig. 2 is an enlarged elevational and sectional view of the keeper and hasp;

Fig. 3 is a transverse section taken on line 3—3 of Fig. 2;

Fig. 4 is a transverse section taken on line 4—4 of Fig. 2;

Fig. 5 is a vertical section taken on line 5—5 of Fig. 2;

Fig. 6 is a vertical section taken on line 6—6 of Fig. 2;

Fig. 7 is an elevational view of the keeper face plate;

Fig. 8 is an elevational view of the filler plate; and

Fig. 9 is an elevational view of the keeper plate.

Referring to the drawings in detail, a standard steel hasp consisting of sections 11, and 12, hinged at 13, is mounted on the inside of a steel door frame 14, being preferably mounted thereon by welding the section 11 to the frame 14. The section 12 of the hasp is provided with a slot 15 (Fig. 4) for receiving a keeper element or bolt 16 mounted on a rectangular keeper plate 17. This keeper bolt 16, in accordance with my invention, is made of hard lead or other material having

considerable strength, but still capable of being sheared fairly easily, and is fixedly secured to a steel plate 17, the openings in said plate which receive the ends of the bolt being countersunk, as illustrated at 18, so that after the ends of the bolt have been inserted through the plate they may be peened over to securely anchor the bolt in place.

The keeper bolt 16 and plate 17 are removably mounted on the inside of the door 19, in position for the bolt to be engaged by section 12 of the hasp, by means of an assembly consisting of a face plate 21 to which is welded a filler plate 22, each of said plates being provided with four bolt holes 23 for receiving round-headed bolts 24, the latter extending through the door from the outside and serving to removably secure the plate assembly to the inside of the door by means of nuts 25 which engage the inner threaded ends of said bolts and clamp the plate securely to the inside of the door.

The filler plate 22 is provided with a rectangular opening 26 (Fig. 8) for receiving keeper bolt plate 17, and the face plate 21 is provided with a slotted opening 27 (Fig. 7) for receiving keeper bolt 16. It will be apparent that the keeper bolt and plate assembly is thus removably secured to the inside of the door and that plate 17 and keeper bolt 16 are likewise removably mounted in the plate assembly, it merely being necessary to remove bolt nuts 25, whereupon plates 21 and 22 may be removed, after which plate 17 and bolt 16 may then be removed from the plate assembly. Normally the hasp is locked to the keeper bolt by a padlock 28 (Fig. 5) since the invention is intended primarily for use on doors which are normally locked from the inside, for example in bonded distillery rack warehouses, and when so used a government seal may be provided, consisting of a seal 29 (Fig. 2) and a wire 31, the latter extending through a hole 32 in face plate 21 and a hole 33 in one of the bolt nuts 25.

In accordance with my invention, means is provided for shearing or cutting off keeper bolt 16 to permit of emergency release of the hasp even though it remains normally locked by padlock 28. To this end I provide a hardened steel blade 34 which is mounted for vertical sliding movement against the inner surface of face plate 21 by means of a pair of guide brackets 35 fixedly

secured to face plate 21, and each consisting of a steel half-channel shaped strip the lower ends and sides of which are closed, the upper ends being open, the brackets being oppositely disposed as illustrated in Fig. 2, to provide guide tracks for vertical movement of blade 34. The lower end of blade 34 is ground to a cutting edge 36 which normally rests against the upper side of keeper bolt 16, as illustrated in Fig. 5, and the upper end of said blade is flanged to provide an exposed inwardly projecting flange or lip 37 which is reinforced by a rib 38. It will be apparent that a downward blow on flange 37 will force the knife-edge 36 of the blade through the lead keeper bolt 16, severing the latter and permitting the portion thereof carrying padlock 28 to be pulled out, thus freeing hasp section 12, and permitting emergency opening of the door. For convenience a metal headed hammer 39 (Fig. 1) is hung on the door frame 14 adjacent the hasp keeper, being preferably chained to the frame by a chain 41 so that it will always be available for striking the knife blade 34 to effect emergency opening.

Once emergency opening has been effected the severed keeper bolt 16 may easily be replaced by simply breaking the seal 29, removing bolt nuts 25, whereupon plate assembly 21-22 and keeper plate 17 may be removed. A new lead keeper bolt 16 may then be secured to plate 17. Said plate, with the new bolt therein, can then be reinserted from the rear into the opening 26 in filler plate 22, the assembly then being secured back to the inside face of the door by bolt nuts 25. A fresh government seal 29 may then be secured in place and the padlock 28 reinserted through keeper bolt 16 to re-lock the door from the inside.

While I have particularly illustrated and described the application of the novel safety hasp keeper to the inside of exit doors which are required to be normally locked, as in bonded distillery rack warehouses, it will be apparent that the device may be applied generally to doors for which emergency opening may be required.

What I regard as new and desire to secure by Letters Patent is:

1. An emergency release mechanism for door locks comprising a locking element, a keeper element, means for supporting the keeper element in position to be engaged by said locking element, the keeper element, when so engaged, being adapted to receive a lock to secure the door in normally locked position, and manually operable means, including a knife member carried by said keeper element supporting means and formed of a material harder than the keeper element, for cutting said keeper element to release it from the locking element and allow opening of the door without requiring removal of the lock.

2. An emergency release mechanism for door locks comprising a hasp, a keeper element, means for supporting the keeper element in position to be engaged by said hasp, the keeper element, when so engaged, being adapted to receive a lock to secure the door in normally locked position, said keeper element being formed of hard lead or other readily shearable material, and manually operable means, including a knife member carried by said keeper element supporting means, for cutting said keeper element to release it from the hasp and allow opening of the door without requiring removal of the lock.

3. An emergency release mechanism for door locks comprising a locking element, a keeper ele-

ment, means for supporting the keeper element in position to extend through said locking element and receive a lock to secure the door in normally locked position, and a knife member mounted on said keeper element supporting means in position to move against said keeper element, said knife member being formed of a harder material than the keeper element and having an exposed portion adapted to be struck to drive the cutting edge thereof through the keeper element, thereby releasing the latter from the locking element to permit opening of the door without requiring removal of the lock.

4. An emergency release mechanism for door locks comprising a hasp, a keeper element, means for supporting the keeper element in position to extend through said hasp and receive a lock to secure the door in normally locked position, said keeper element being formed of hard lead or other readily shearable material, and a knife member mounted on said keeper element supporting means in position to move against said keeper element, said knife member having an exposed portion adapted to be struck to drive the cutting edge thereof through the keeper element, thereby releasing the latter from the hasp to permit opening of the door without requiring removal of the lock.

5. An emergency release mechanism for door locks comprising a hasp adapted to be fastened to a door frame and a keeper assembly, including a mounting plate, a keeper element secured to said plate and adapted to extend through said hasp and receive a lock to secure the door in normally locked position, means for removably fastening said plate to the door, and a knife member carried by said fastening means for cutting said keeper element to release it from the hasp and allow opening of the door without requiring removal of the lock, said keeper element being formed of a material that will shear when the knife member is struck and driven against it.

6. An emergency release mechanism for door locks comprising a locking element adapted to be fastened to a door frame, a keeper element engageable by said locking element and adapted, when so engaged, to receive a lock to secure the door in normally locked position, and manually operable means for cutting said keeper element to release it from the locking element and allow opening of the door without requiring removal of the lock, said means including a keeper mounting plate, a face plate and a filler plate secured thereto, the latter having an opening for receiving and holding the keeper mounting plate and the face plate having an opening for receiving the keeper element, a knife member, guide means carried by said face plate for holding said knife member in position for movement against the keeper element, said knife member being formed of a harder material than the keeper element and having an exposed portion adapted to be struck to drive the cutting edge thereof through the keeper element, and means for removably fastening the face plate and filler plate to the door.

7. An emergency release mechanism for door locks comprising a locking element adapted to be fastened to a door frame, a mounting plate, a keeper element having one end thereof secured to said plate, the other end being engageable by said locking element and adapted, when so engaged, to receive a lock to secure the door in normally locked position, means for removably fastening said plate to the door, and a knife member carried by said fastening means for cutting

the keeper element to release it from the locking element and allow opening of the door without requiring removal of the lock, said knife member being formed of a harder material than the keeper element and said mounting plate likewise being formed of a harder material than the keeper element to permit the end of the latter to be readily driven from said plate, after severance, to facilitate insertion of a new keeper element.
